UNITED STATES PATENT OFFICE.

WILLIAM A. HARTLINE, OF PENNS GROVE, NEW JERSEY.

HAT-PIN.

1,259,733.

Specification of Letters Patent. Patented Mar. 19, 1918.

Application filed November 22, 1917. Serial No. 203,407.

To all whom it may concern:

Be it known that I, WILLIAM A. HARTLINE, a citizen of the United States, residing at Penns Grove, in the county of Salem and 5 State of New Jersey, have invented certain new and useful Improvements in Hat-Pins, of which the following is a specification.

This invention relates to hat pins, and more particularly to a hat pin provided with 10 means for securing the same in a hat.

One of the main objects of the invention is to provide a hat pin of simple construction and operation having means for preventing accidental withdrawal of the same 15 from a hat. A further object is to provide a hat pin of the character stated of simple construction and neat appearance which may be produced at relatively small cost. A still further object is to provide a device for 20 securing a hat pin in a hat which may be readily applied to hat pins of standard construction. Further objects will appear from the detailed description.

In the drawings:—

25 Figure 1 is a side view of a hat pin having a securing means constructed in accordance with my invention applied, the securing means being shown in section and in inoperative or retracted position,

30 Fig. 2 is a similar view showing the securing device in extended or operative position,

Fig. 3 is a section on line 3—3 of Fig. 1,

Fig. 4 is a section on line 4—4 of Fig. 1,

35 Fig. 5 is a perspective detail of the locking spring and the rod carrying the same,

Fig. 6 is a view similar to Fig. 2 of a modified form,

Fig. 7 is a detail central sectional view 40 through the form of locking device shown in Fig. 6, and

Fig. 8 is a fragmentary detail showing the locking device as used.

Referring more particularly to Figs. 1 to 5 inclusive—the hat pin A is provided with 45 a suitable head 1 and shank 2 having the point 3 for insertion through the crown of a hat. Shank 2 is provided, in its upper end portion, with an axially extending bore 4, the upper end portion of the shank being 50 intermediately threaded to receive the threaded stud 5 of head 1, the head and shank thus being detachably secured together. A rod 6 is slidably mounted in bore 4, this rod being of such diameter as to fit snugly with- 55 in the bore, but being of considerably less length than the bore so as to be freely slid-

able axially of the same in either direction. A spring steel locking wire spring 7 is carried by rod 6 and is so shaped as to be normally pressed outwardly radially of the rod 60 so as to project through the slot 8 communicating with bore 4 when the spring is moved into register with this slot, as in Fig. 2 of the drawings. The outer end portion of spring 7 is bent to provide an inwardly 65 directed arm 9 disposed at a right angle to the body of the spring, and an outwardly directed arm 10 disposed at a right angle to arm 9. In assembling the device, spring 7 is first bent to provide the arm 9 which is 70 inserted through the diametrically extending bore 9^a of rod 6, this bore communicating at one end with the axial groove 9^b formed in the peripheral face of rod 6 and, at the other end, with the short groove 10^a 75 formed in the opposite face of the rod. After the arm 9 of spring 7 has been inserted through the diametrical bore 9^a, and the spring 7 is seated within the groove 9^b, the portion of this arm which projects beyond 80 the rod is then turned outwardly at a right angle so as to fit snugly within groove 10^a thus producing the arm 10, as shown. The rod 6 with the locking spring 7 thus secured in the same is then inserted into the axial 85 bore 4 through the upper end of shank 2 in such position that the spring 7 will be moved into register with slot 8 when the rod 6 is moved into this extreme position toward the head 1 of the pin. A collar 11 is 90 slidably mounted on shank 2. This collar is provided with a threaded aperture to receive the set screw 12 having the integrally inwardly extending pin 13. This pin 13 projects into the diametrical bore 14 adjacent the inner end of rod 6. This bore is positioned in the plane of bore 9^a, and the pin 13 which extends into the same also projects through slot 8. By this means, I insure 95 that rod 6 will be at all times maintained 100 in proper position in bore 4 for bringing spring 7 into register with slot 8 when the rod is moved into its innermost position. The movement of rod 6 from one extreme position to the other may be readily accomplished by means of the collar 11. When the rod 6 is moved into its extreme outward position the spring 7 will be depressed and forced into the groove 9^b of the rod so as to be contained entirely within the outline of 110 the shank of the pin, as in Fig. 1 of the drawings. When the securing spring is in

this position, the shank 2 of the pin may be readily inserted through the crown of a hat in the ordinary manner. After the pin has been inserted into the hat crown, the collar 11 may be moved toward the head 1 so as to bring the spring 7 into register with slot 8 thus causing the spring to project through the slot and engage the inner face of the hat crown thus effectually locking the pin 10 against accidental withdrawal, as in Fig. 8 of the drawings, in which figure the locking spring 7 engages inside of the hat crown B. This movement of the collar 11 toward the head 1 of the pin may be accomplished 15 manually, or it may be effected by the simple expedient of pushing the shank of the pin through the crown, the engagement of the collar with the hat crown serving to secure the collar against movement while the shank 20 2 is moved forward relative to the collar thus bringing the spring 7 into register with slot 8 as in Fig. 8 of the drawings. When it is desired to withdraw the pin, the collar 11 may be held against movement, the 25 head 1 and shank 2 carried thereby being drawn outward thus depressing the spring 7 so as to force the same into the groove 9^a of rod 6, after which the pin may be easily removed in the same manner as a hat pin 30 of standard construction.

In the modified form shown in Figs. 6 and 7 of the drawings, the shank 2 is shortened and a tubular member 16 is interposed between the shank and head 1. This tubular member is interiorly threaded at its inner end to receive the threaded stud 5 of the head, and is also interiorly threaded at its outer end to receive a similar stud 17 carried by shank 2. This tubular member 16, 35 when in position, forms practically an integral portion of the pin, and replaces the portion of the pin containing the axial bore 4 in the form shown in Figs. 1 and 2 of the drawings. This tubular member 16 contains 40

the rod 6 and the locking spring carried 45 thereby, and is operated by means of the collar 11 in the same manner as in the form originally described. The object of providing this tubular member is to permit this locking device to be quickly and easily applied to hat pins of standard construction. To apply this device, it is only necessary to shorten the shank 2 so as to accommodate the member 16, reducing and threading the end portion of the shank to provide the 55 threaded stud 17. By this construction my locking device may be quickly and easily applied to a hat pin of ordinary construction at very small cost. When it is desired to disassemble the device constructed as 60 shown in Figs. 6 and 7 it is only necessary to remove the set screw 12, after which the rod 6 and the parts carried thereby may be readily forced out of the tubular member 16 by means of a heavy pin 18, or other suitable 65 instrument, inserted into the same, as in Fig. 7 of the drawings. The device may be as quickly and easily reassembled in a similar manner.

What I claim is:—

In hat pins, a shank having an axial bore and an axially extending slot communicating therewith and of less length than said bore, a rod slidable in said bore, a locking spring carried by the rod and adapted to 75 project through said slot when moved into register therewith, a collar slidable on said shank, and a set screw threaded through said collar and having an integral pin projecting through the slot and into said rod 80 for moving the rod axially of the bore by means of said collar.

In testimony whereof I affix my signature in presence of two witnesses.

WILLIAM A. HARTLINE.
